CLAIM

The ornamental design for a battery charger for a thermal imager, as shown and described.

DESCRIPTION

FIG. 1 is a top perspective view of a battery charger for a thermal imager, shown with the first and second straps in an open configuration;

FIG. 2 is a top perspective view of the battery charger of FIG. 1, shown with the first and second straps in a closed configuration;

FIG. 3 is a bottom perspective view of the battery charger of FIG. 1;

FIG. 4 is a front view of the battery charger of FIG. 1;

FIG. 5 is a rear view of the battery charger of FIG. 1;

FIG. 6 is a left side view of the battery charger of FIG. 1;

FIG. 7 is a right side view of the battery charger of FIG. 1;

FIG. 8 is a top view of the battery charger of FIG. 1; and,

FIG. 9 is a bottom view of the battery charger of FIG. 1.

The broken lines shown in the drawings depict portions of the battery charger that form no part of the claimed design.
